UNITED STATES PATENT OFFICE.

CLYDE L. KNOTT AND EDWARD ERICKSON, OF BEVERLY, MASSACHUSETTS, ASSIGNEES
TO UNITED SHOE MACHINERY CORPORATION, OF PATERSON, NEW JERSEY, A COR-
PORATION OF NEW JERSEY.

COMPRESSING MACHINE.

Application filed August 24, 1920. Serial No. 405,590.

To all whom it may concern:

Be it known that we, CLYDE L. KNOTT and EDWARD ERICKSON, citizens of the United States, residing at Beverly, in the county of Essex and Commonwealth of Massachusetts, have invented certain Improvements in Compressing Machines, of which the following description, in connection with the accompanying drawings, is a specification, like reference characters on the drawings indicating like parts in the several figures.

This invention relates to compressing machines and, in the embodiment selected for illustration and description herein, is shown as applied to a machine for compressing or condensing flat articles or blanks of sheet material such, for example, as heel lifts.

The improvement of top lifts for the heels of boots and shoes by compression or condensation is very extensively practised and the present invention has an important application in machines for this purpose. One type of compressing machine in extensive use has a blank compressing mold carried by a vertically reciprocable, toggle actuated cross head and co-operating with a stationary die. In order to attain the necessary pressure the parts of such a machine, including the moving parts, must be very rigid and heavy and, as a result, the speed of operation is limited. One important object of the present invention is to produce a compressing machine which shall be capable of greatly increased speed of operation and will consequently have a much larger output than the machines heretofore used. In the illustrated embodiment of the invention this object is attained in a machine having a plurality of compressing molds movable successively into blank receiving position and capable of a complete cycle of movement in approximately the same time required by machines of the type above referred to for one complete reciprocation. The natural result of this is that the output of the machine is increased as many fold as there are compressing molds—there being three such molds in the illustrated machine which, consequently, has approximately three times the productive capacity of the machines now in commercial use. The molds are preferably mounted upon a rotary carrier, which is provided with mechanism for

turning it continuously in the same direction. In the present invention the difficulty of securing in a rotary machine the very heavy pressure required in the treatment of the blanks has been successfully overcome by actuating the compressing die by toggle mechanism carried by, and moving with, the rotating mold carrier. As shown, in the drawings, a separate toggle is provided for each mold and the entire mold and toggle mechanism is contained within the periphery of the carrier, the toggle pressure reacting upon the carrier casting. It thus becomes practicable to make a very powerful compressing mechanism of minimum weight.

Important features of the invention are concerned with mechanism for feeding blanks to the compressing molds, improved mold mechanism affording increased strength and durability, and other features of improvement which will become apparent from reading the following detailed description of the illustrated embodiment of the invention, in connection with the accompanying drawings, in which—

Fig. 1 is a view in front elevation of a machine embodying the invention;

Fig. 2 is a side elevation looking from the right of Fig. 1;

Fig. 3 is a view, partly in elevation and partly in section, upon the line 3—3 of Fig. 1;

Fig. 4 is a front elevation of the rotor with parts broken away to reveal the internal construction of the molds, the plane from which the view is taken being upon approximately the line 4—4 of Fig. 2;

Fig. 5 is an enlarged view, in front elevation, showing the lower end of the blank magazine and two positions of the feeding mechanism;

Fig. 6 is a section upon the line 6—6 of Fig. 3;

Fig. 7 is an enlarged view showing more fully parts of the internal mechanism not clearly revealed in Fig. 6;

Fig. 8 is a section upon the line 8—8 of Fig. 1, showing the mechanism for controlling the application of power to the machine;

Fig. 9 is an inverted plan view of a detail of the blank feeding mechanism;

Fig. 10 is a section upon the line 10—10 of Fig. 9;

Fig. 11 is a plan view of the blank feeding picker; and

Fig. 12 is a front elevation of the mechanism shown in Fig. 11.

- 5 The operative mechanism of the machine is supported upon a base 20 in which is mounted a stationary shaft 22 about which the rotating member of the machine turns.
- 10 A bracket 24, bolted to the side of the base 22, affords a support for an electric motor 26 or other suitable source of power. The motor shaft 28 carries a pinion which meshes with a gear 30 (see Fig. 8) loosely mounted upon the driving shaft 32. A conical member 34 secured to the driving shaft 32 cooperates with a conical internal face formed in the gear 30 to constitute a friction clutch. In order to engage the clutch the gear 30 is shifted toward the left, as seen in Fig. 8, by 15 a clutch shifting mechanism comprising a collar 36 bearing against the hub of the member 30 and actuated by a toggle 38 connected to bell crank members 40, the inner arms of which react against a collar 42 adjustably secured upon the driving shaft. The toggle 38 is operated by either one of 20 a pair of hand levers 44, 46 located at the rear and front of the machine respectively and connected by a bar 48.
- 25 Referring again to Fig. 8, 50 indicates a hand crank which may be used to turn the machine over without the application of power, when desired for purposes of adjustment, by pushing inwardly against the 30 tension of a spring 52 and meshing the crown ratchets 54, one of which is secured to the driving shaft 32.
- 35 Also secured to the driving shaft is a pinion 56 meshing with the large ring gear 58 which is shrunken upon the periphery of the rotor 60 journalized to rotate about the stationary shaft 22. The teeth of the gear 58 are covered by a protecting casing 62.
- 40 The mold carrier or rotor 60 consists of a suitably formed casting best illustrated in Fig. 4. Three blank compressing molds are mounted in recesses in the rotor member and inasmuch as their construction is identical it will suffice to describe one of them. A 45 mold member 64 (see Figs. 3 and 4), provided with a handle 66 to facilitate its insertion and removal from the rear of the machine when molds are to be changed for blanks of different sizes or shapes, is held 50 in the mold carrier by flanges 68 sliding in suitably formed grooves in the rotor casting. A lower die member 70 having a total height equal to the height of the mold member 64 and having a blank engaging face which exactly 55 fills the mold cavity is provided for each mold, the assemblage of the members 64 and 70 constituting an interchangeable unit and three such units being provided for each size or shape of blank to be operated 60 upon.

The lower die 70 rests upon the upper face of a block 72 which forms one part of an ejecting plunger. The other part of the plunger consists of a cup shaped member 74 in which is received a reduced lower end 75 of the block 72. Pins 76 prevent relative rotation of the members 72 and 74 while permitting the vertical spacing of said members with relation to each other to be varied by the insertion of shims 78 of different thickness between said members. As will presently appear the purpose of this adjustment is to accommodate the mold to blanks of different thicknesses. The member 74 has a depending stem 80 which is engaged by the arm 82 of an ejecting lever to raise the lower die 70 until its surface is flush with the top of the mold member 64 to permit a compressed blank to be removed from the mold.

The upper die 84 of the mold is removably held in a dove-tail slot in the lower face of a sliding plunger 86 confined by gibs 88 to a flat guiding surface formed in the rotor casting. The plunger 86 is reciprocated vertically by a double toggle mechanism comprising a pair of links 90 and a pair of links 92. One end of the toggle 90 is pivotally connected to the plunger at 94, the opposite end being pivoted at a point 96 which is stationary with respect to the rotor casting. The toggle 92 has one end pivoted to the center of the toggle 90 and the opposite end pivoted to the rotor casting at the pivotal point 96 of the toggle 90 belonging to the next compressing mold of the series. The center pin of the toggle 92 carries a cam roll 100 which travels in a stationary, closed path 102 cut in the rear face of a large disk 104 (see Fig. 3) secured to the stationary shaft 22. The center line of the cam path is shown by the broken line 104 in Fig. 4. It will be understood that as the rotor 60 rotates the travel of the cam roll 100 around the cam path will cause the plunger 86 to be reciprocated at times determined by the shape of the cam path.

The plunger 86 carries a projecting cam member 106 cooperating with a cam roll 108 at the end of an arm 110 mounted for movement about a pivot 112 in the arm 114 of the ejecting lever, the opposite arm 82 of which acts upon the spindle 80. The ejecting lever is movable about one of the pivots 96.

A ring 118 is immovably secured in the mold recess of the rotor casting and pins 120 extend downwardly from the ring 118 into recesses in a ring 122 located in the space below the ring 118. This pin connection is such that the ring 122 is freely movable up and down but is held against rotation. The ring 122 is internally threaded and the member 74 is correspondingly threaded externally, one of said members be-

ing screwed into the other. By rotating the die supporting member 72 by means of a spanner wrench inserted in the holes above the pins 76 rotation will be imparted to the member 74 through the said pins and by this means the ring 122 will be adjusted vertically with respect to the member 74. The ring 122 is a stop member to determine the upper limit of movement of the die support which it does by engagement with the fixed ring 118 and the purpose of the described adjustment is to compensate for shims 78 of various thicknesses which may be used, the end in view being that when the ejecting mechanism occupies the position shown in the lower right hand mold in Fig. 4 the lower surface of the lower die member 70 shall be flush with the lower surface of the mold member 64 so that the mold assemblage may be readily withdrawn from the machine. The yielding connection 124 between the members 110 and 114 permits the cam 106 to operate fully regardless of the adjustment of the ring 122 and the said cam is designed to impart sufficient movement to the arm 110 to insure that the ring 122 shall always engage the stop ring 118 when the ejecting plunger is up. It is apparent that the supporting member 72 would in any event engage and be stopped by the lower face of the mold member 64 when the plunger is elevated but if other means were not provided for limiting the upward movement of the plunger the pressure of the supporting member 72 against the mold member 64 would be sufficient to prevent the withdrawal of the latter when it was desired to change molds.

A stationary blank magazine 126 is arranged to contain a stack of the blanks to be operated upon. The magazine is supported by a stationary bracket 128 having a ring portion secured to a hub 130 formed upon the base 20 and in which the stationary shaft 22 is mounted. A plate 132 has a tongue and groove connection with the upper surface of the bracket 128 permitting it to be adjusted forwardly and rearwardly of the machine. A binding bolt 134 serves to secure the plate 132 in adjusted position.

Two bracket members 136, 138 are adjustable transversely of the plate 132 by means of a right and left screw 140 and are secured in adjusted position upon the plate by binding bolts 142. Each of the bracket members 136, 138 carries one half of the magazine, said half consisting of an angular member 144 for engaging one breast corner of the lift and a plate 146 set at an angle of 45° to the breast edge of the lift for engaging the curved edge thereof.

It will be understood from the foregoing that by adjustment of the plate 132 the magazine as a whole may be adjusted forwardly and rearwardly of the machine and that by

adjustment of the bracket members 136, 138 the two halves of the magazine may be adjusted toward or from each other to accommodate lifts of different widths. Only one other adjustment is required to make the magazine universally applicable to lifts of all sizes and shapes and that is adjustment of the plates 146 toward and from the breast engaging members 144. The following provision is made for this adjustment. Each of the plates 146 is supported by a pair of properly shaped rods 150, 152, the ends of which are threaded into sleeves 154, 156 rotatably mounted in the suitable bearings. The ends of the sleeves 154 are provided with bevel gears 158 meshing with corresponding bevel gears 156 secured to the ends of a connecting shaft 160. By rotating the sleeves 154, 156 which act as nuts upon the threaded portions of the rods 150, 152, the plate 146 is moved forwardly or rearwardly and by reason of the geared connections just described, is always maintained parallel to the member 144. Squared heads 162 are conveniently located for engagement by a wrench to effect the necessary adjustments.

Referring now to Figs. 1 and 5 the left hand half of the magazine has provision for a limited amount of vertical movement under conditions to be more fully described hereinafter. On this side of the magazine the shaft 160 passes loosely through a pair of lugs 170 projecting from the bracket member 136. The right hand faces of these lugs are also flat and are slidably engaged by a flat face 172 upon the support for the blank engaging members constituting the left hand half of the magazine in the lower end of which is mounted the rotatable cam roll 174. By virtue of this construction the left hand half of the magazine is capable of rising and descending under the influence of a cam to be described later.

The mechanism for removing blanks from the magazine and feeding them to the compressing molds will now be described. A picker is provided for each compressing mold, the said pickers acting in succession to remove blanks from the magazine and present them to the corresponding feeding mechanisms which transfer them to the molds in succession.

Referring now to Figs. 5, 6 and 7, 176 indicates a picker arm pivoted at 178 to a bracket 180 projecting from the side of the frame which supports and guides the feeding mechanism. The picker arm has an extension 182, the end of which is bifurcated to receive the end of a cam lever 184 carrying a cam roll 186. A yielding connection between the cam lever and picker arm is provided by a pair of spring pressed plungers 188, 190. The cam roll 186 is actuated by a stationary cam 192 to impart the necessary movements to the picker arm

at the proper times. As is apparent from Fig. 2 the path of rotation of the pickers is such that they pass in succession beneath the magazine in position to remove blanks successively from the lower end thereof.

Referring to Figs. 11 and 12 each picker member comprises a plate 194 secured to the end of the picker arm by screws 196 and having upwardly and inwardly turned fingers 198, 200. The direction of motion of the picker is indicated by the arrow in Fig. 11. By removing the screws 196 other plates 194 of different sizes may be applied to provide for different sizes of blanks to be handled. The magazine will be so adjusted that the edge of the finger 198 will pass just in front of the breast line of the lowermost heel lift in the magazine and as the picker advances, the finger 200 will engage the side edge of the lift and remove it from the magazine. A pin 202 is secured in a slot 204 by a thumb nut 206. By slackening the thumb nut the position of the pin 202 longitudinally of the slot may be changed and it is intended that the pin shall be so adjusted in the slot that it will afford a gage for the rear edge of the lift as the latter rests upon the picker plate. The picker plate supporting member 207 has a vertically slidable dove-tail connection 208 with the end of the picker arm 176 and a compression spring 210 between the members 207 and 176 provides for relative yielding movement between the two. The pin 202 passes through a slot in a U-shaped presser member 212 adjustably secured in the end of the picker arm but incapable of yielding relatively thereto. The connection between the presser member 212 and the end of the picker arm comprises a dove-tail connection 214, permitting adjustment of the presser member forwardly and rearwardly relatively to the picker arm, the presser member being secured in adjusted position by a binding screw 216.

A stop screw 218 arranged to be engaged by an abutment 220 on the picker arm extension 182 provides for adjustment of the position occupied by the picker with relation to the magazine when it is about to remove a lift therefrom, as will be apparent from Fig. 5.

A stack of lifts in the magazine 126 is supported by the peripheral surface of a cylindrical drum 222 carried by a spider 224 secured by bolts 226 to the rotor member 60 and rotating therewith. Recesses 228 are provided in the periphery of the drum 222 for the reception of the pickers, and the proper adjustment of the stop screw 218 is such that when the parts are in the position shown in full lines in Fig. 5, the upper surface of the plate 194 is substantially secant to the periphery of the drum and the upper face of a lift of aver-

age thickness resting upon the plate is approximately tangent to the surface of the drum.

The drum 222 has a frusto-conical extension 230 which is engaged by the roll 174 and serves to support the vertically movable left-hand half of the blank magazine. At intervals of 120° about its circumference the conical extension 230 is intersected by planes parallel to its axis, forming flat, substantially triangular faces 232 in alignment with the recesses 228. The relation between the blank magazine and the conical extension 230 is such that as the magazine is adjusted forwardly or rearwardly of the machine by adjustment of the plate 132 the roll 174 bears upon portions of the cone 230 of respectively greater and smaller diameters.

The purpose of making the left-hand half of the magazine vertically movable will now be apparent. It will be understood that the lower ends of the members of the left hand half of the magazine are located to permit the lowermost blank in the stack to be advanced toward the left beneath them to remove the said lift from the magazine while retaining the superposed lifts in stacked relation in the magazine. As the picker moves toward the left from the position shown in full lines in Fig. 1, portions of the upper face of the lift being removed which are progressively nearer the axis of rotation will pass under the lower ends of the left hand magazine members which must, therefore, be progressively lowered, in order to preserve unchanged the spaced relation between their lower ends and the upper face of the said lift until the center of the lift passes under them, after which they must be raised progressively until the lift has been completely removed from the magazine. Inasmuch as the center of the roll 174 is substantially in alignment with the left hand edges of the lifts in the stack and the flat face 232 which passes under the roll, is parallel to and in alignment with the lift, the left hand magazine section will be raised and lowered in proper time relation to the movement of the lift to permit the removal of the lowermost lift and insure the retention of the remaining lifts on the stack. The triangular shape of the face 232 provides automatically for reduction of the duration of the up and down movement just described, when small lifts are being handled, since in that case the proper condition of adjustment will locate the breast members 144 of the magazine further to the rear of the machine than when large lifts are being handled and the roll 174 will consequently be engaged by a narrower part of the triangular flat face 232. By reason of the conical shape of the member 230 the total rise and fall of the vertically movable magazine sec-

tion will also be less as the magazine is adjusted toward the right, which is correct, since the extreme edges of a narrow lift project a less distance from the periphery 5 of the drum 222 than do those of a wide lift.

The mechanism for removing a blank from the magazine having been described, we will now proceed to describe the means by which the blank is transferred from the picker to 10 the compressing mold. By reference to Fig. 5 it will be seen that the shape of the stationary cam 192 which controls the swinging of the picker arm about its pivot 178 is such that as rotation proceeds in the 15 direction of the arrow the picker with the blank upon it will be moved from the position shown in full lines to that shown in broken lines. In the latter position the blank indicated by the reference character α 20 will be pressed upwardly, flatwise, into the under side of the feeding device which is to transfer it to the mold.

The details of the feeding mechanism are best illustrated in Figs. 1, 3, 6, 7 and 9. The 25 three feeding mechanisms being identical in construction and operation, it will be sufficient to describe one of them in detail. Gear teeth 234 are cut in the periphery of the stationary cam disk 102. A spur gear 236 30 meshes with the stationary gear 234 and moves around it in a planetary path. Secured to the shaft 238 of the gear 236 and rotating with the latter is a bevel pinion 240 which meshes with a larger bevel gear 242 35 (see Figs. 6 and 7). In the blank face of the bevel gear 242 is a crank pin 244 connected by the link 246 to a stud 248 mounted in a slide 250 which is movable forwardly and rearwardly of the machine in guide 40 grooves formed in the supporting frame 252, being maintained in the said grooves by gibs 254. Upon the opposite end of the stud 248 is a loose pinion 256 which meshes with a 45 stationary rack 258 secured to the frame 252 and with a rack 260 formed on the under side of a slide 262 guided for relative forward and rearward movement in a secondary slide 264.

As illustrated in Fig. 3 the slide 264 is 50 provided with bosses 266, 268 between which is located the boss 270 which projects upwardly from the slide 262. The boss 270 carries spring pressed plungers 272 projecting in opposite directions in position to engage the bosses 266 and 268 forming a connection between the slides 262 and 264 which is yielding in both directions. It will be understood that rotation of the gear 242 will effect reciprocating movement of the slide 55 250 through the crank pin 244 and connecting rod 246 and that the rack and pinion mechanism 256, 258, 260 will translate this reciprocating motion into reciprocating motion of the slide 262 through twice the 60 distance moved by the slide 250.

The limit of the rearward movement of the slide 264 is determined by the engagement of a lug 274 projecting downwardly from the slide with the front face of that portion of the rotor casting 60 in which 70 the compressing mold is located. The connection between the slides 262 and 264 is capable of sufficient yield to allow the slide 262 to overthrow somewhat and this is desirable in order to insure that all the back 75 lash in the gearing and connections shall be taken up and that the stop lug shall engage that part of the member 60 which it is intended to strike. A blank engaging member 278 is mounted upon the slide 264 80 and is forwardly and rearwardly adjustable with relation thereto by virtue of a dove tail connection and a right and left screw 280 threaded into the lug 266 and a lug 282 depending from the slide 278. 85

A pair of blank edge guides 284 is arranged for equal and opposite transverse adjustment by a T slot mounting 288 upon the member 278 and a pair of right and left screws 290 which are geared together to 90 operate simultaneously. Lugs 292 projecting inwardly from the guide members 284 engage the corners of the blank to move the latter rearwardly when the slide 264 moves in that direction. 95

As illustrated by broken lines in Fig. 5, the picker presses the lift α up into the now inverted feeding mechanism locating it between the guide members 284 and back of the lugs 292, as shown at α in Fig. 9, which shows the relation of the lift to the parts which engage it but shows the parts in a position which is assumed later in the operation of the machine. The lift is supported by a series of fingers 294 which extend 100 from the member 278 and assume an interdigital relation to a set of stationary fingers 296 over which the lift passes on its way to the mold.

The purpose of the yielding mounting of 110 the picker plate upon the end of the arm 176 will now be apparent, inasmuch as the spring 210 may yield to permit sufficient movement of the arm 176 to cause the presser member 212 which is rigid with the arm to press the lift up against the fingers 294. The timing is such that the slide 264 is projected forwardly to lift receiving position at the time when the parts reach the 115 position shown in broken lines in Fig. 5. Immediately after the picker has delivered the lift to the slide the slide starts to move 120 rearwardly, continuing until its movement is stopped by the stop lug 274 striking the casting 60, at which time the parts are in the relation shown in Figs. 3 and 9, the lift whose course through the machine we 125 have been tracing being in the position indicated by α .

Two yieldingly mounted fingers 298, 130

pressed downwardly by springs 300, press upon the lift as it advances. When the lift has reached the position shown in Fig. 3 it has passed the shoulders 302 upon the lower edges of the fingers 298 and is positively prevented by the shoulders from moving forwardly when the feed slide next advances. The fingers 298 are carried upon and adjusted with the guide members 284 and the parts are maintained in assembled relation by a pair of overhanging arms 304. The correct position of the fingers 298 is as shown in Fig. 3, with their inner ends closely adjacent to the edge of the mold cavity. It will be understood that the edges of the cavities of molds of different sizes will occupy different positions and, therefore, provision for longitudinal adjustment of the fingers 298 is necessary when molds are changed. To this end the arms 304, which determine the longitudinal position of the fingers, are carried by a suitably formed casting 305 (see Figs. 2 and 6) which has a tongue and groove connection with the supporting bracket 252, as indicated at 307. By reason of this tongue and groove connection the casting 305, together with the arms 304 and the mechanism supported thereby, may be adjusted longitudinally until the inner ends of the fingers 298 occupy the correct relation to the edge of the mold cavity, a bolt and binding nut 309 being provided for securing the parts in their adjusted position. A suitably graduated scale 311 (see Fig. 2) enables the operator to determine the proper adjustment for the size of mold being used.

The transfer of the lift from the picker to the compressing mold occurs in two stages, Fig. 3 showing the position of the lift at the end of the first stage. As already explained the shoulders 302 upon the fingers 298 maintain the lift in this position while during the next forward movement of the feed slide the spring pressed yielding fingers 306 (see Figs. 9 and 10) pass around the side edges of the lift and engage the breast edge thereof. On the next inward movement of the slide the lift is fed inwardly by the fingers 306 until, at the end of the second stage, it reaches the position occupied by the lift b (Figs. 4 and 9). In this position the lift is directly over the compressing mold, the lower die member 70 of which is ready to receive it, as shown in Fig. 3. The guide members 284 are beveled, as shown at 308 to permit the upper compressing die 84 to pass between them readily without danger of catching upon and breaking them.

When the lift has reached the position indicated at b the plunger 86 descends, causing the lift to be forced into the compressing mold and subjected to pressure. During the compressing operation the feeding slide

is again advanced during which time a second pair of fingers 306', similar to the fingers 306 passes around and moves past the edges of the die 84. After the lift is compressed the plunger 86 is again elevated and the lower die 70 rises until the compressed or condensed lift is flush with the top of the mold. Upon the next inward movement of the feed slide to bring the next lift to the compressing mold the compressed lift upon the die 70 is engaged by the fingers 306' and removed before the incoming lift reaches the die. The lift removed by the fingers 306' is permitted to slide down an incline 310 and drop into any convenient receptacle beneath.

312 indicates a platform upon which the operator may stand when it is desired to fill the magazine with blanks.

The operation of the machine will be understood from the preceding description but for the sake of easy comprehension may be briefly recapitulated at this point. A stack of blanks to be operated upon is at all times maintained in the magazine 126 and the machine is operated continuously.

The rotor 60 turns continuously in the direction indicated by the arrows in the various figures of the drawings. As each picker approaches the blank magazine it is turned by the cam 192 into position to pick the lowermost blank from the magazine; as the blank is removed the left hand section of the magazine is automatically lowered and elevated to control the delivery of the blank. There being three pickers upon the rotor, three blanks will be removed from the magazine during each revolution.

After removing a blank from the magazine the picker arm is swung by its cam 192 into the position shown in broken lines in Fig. 5 pressing the blank up flatwise into the corresponding feeding mechanism. The feed slide is at this moment projecting into blank receiving position and immediately after the reception of the blank starts rearwardly, carrying the blank through the first stage of its feeding movement and simultaneously transferring the blank received during the previous cycle of the machine through the second stage of its feeding movement and depositing it in the compressing mold. As the rotation of the rotor continues the last mentioned blank is compressed and the feed slide moves forward until it reaches the broken line position of Fig. 5 ready to receive the next blank from the picker. Simultaneously with the transfer of a blank to the compressing mold the previously compressed blank which has been ejected from the mold cavity is removed and allowed to slide down the incline 310.

This operation is continued indefinitely, it being understood that the feed slide dur-

ing each inward movement acts upon three blanks, viz, the one received from the picker and moved through the first stage of its path toward the compressing mold, the blank 5 being moved through the second stage and delivered to the compressing mold, and the compressed blank being ejected from the machine.

While one specific object of the embodiment of the invention has been illustrated and described in detail it should be understood that many of the features of the invention are capable of practical embodiment in forms other than the illustrative 15 construction herein disclosed, which is shown and described by way of illustration only and not by way of limitation and that for a definition of the exact scope of the invention reference is to be had to the appended claims.

Having described our invention, what is claimed as new and desired to be secured by Letters Patent is:—

1. A compressing machine having a plurality of compressing mechanisms, a blank magazine, and a plurality of mechanisms for transferring blanks from the magazine to the compressing mechanisms in succession.

2. A compressing machine having a single blank magazine, a plurality of compressing molds, and a corresponding plurality of successively operating mechanisms for removing blanks from the said magazine and transferring them to the respective molds.

3. A compressing machine having a mold carrier, a plurality of compressing molds upon the carrier, mechanism upon the carrier for feeding blanks to the molds in succession, a blank magazine, and means for removing blanks successively from the magazine and transferring them to the feeding mechanism.

4. A compressing machine having a mold carrier, a blank magazine, means for removing blanks successively from the magazine, and a plurality of blank feeding mechanisms upon the carrier movable successively into blank receiving position, to receive blanks from said blank removing means.

5. A compressing machine having a rotating mold carrier, a compressing mold mounted upon the carrier, and mechanism mounted upon the carrier and movable relatively thereto for feeding a blank to the mold.

6. A compressing machine having a rotating mold carrier, a plurality of compressing molds mounted upon the carrier, and mechanism movable relatively to the carrier, mounted thereon and operated by rotation thereof, for feeding blanks to the molds.

7. A compressing machine having a rotat-

ing mold carrier, a compressing mold mounted upon the carrier, and mechanism mounted upon the carrier, movable relatively thereto, and operated by rotation thereof for feeding a blank to the mold.

8. A compressing machine having a rotating mold carrier, a compressing mold upon the carrier, and a blank feeding slide upon the carrier in co-operative relation to the mold.

9. A compressing machine having a rotating mold carrier, a plurality of molds upon the carrier, and mechanism on the carrier and movable relatively thereto for feeding blanks to all the molds.

10. A compressing machine having a rotating mold carrier, a plurality of compressing molds upon the carrier, and a corresponding plurality of mechanisms on the carrier and movable relatively thereto for feeding blanks to the molds.

11. A compressing machine having a rotating mold carrier, a plurality of compressing mechanisms upon the carrier, a blank magazine, and means for transferring blanks from the magazine to the compressing mechanisms in succession.

12. A compressing machine having a rotating mold carrier, a compressing mold mounted upon the carrier, mechanism on the carrier for feeding a blank to the mold, a blank magazine, and means for removing a lift from the magazine and transferring it to the feeding mechanism.

13. In a compressing machine, the combination of a magazine for holding flat blanks, a compressing mold, a feeding device for feeding blanks to the mold, and means for removing a blank from the bottom of the magazine and pressing it flatwise into the feeding device.

14. In a compressing machine, the combination of a magazine for holding flat lifts, a compressing mold, a feeding device for feeding blanks to the mold, and a picker constructed and arranged to remove a blank edgewise from the magazine and insert it flatwise into the feeding device.

15. In a compressing machine, the combination of a blank containing magazine, multi-stage straight line feeding mechanism constructed and arranged to feed blanks under continuous control, and means for removing blanks successively from the magazine and transferring them to the feeding mechanism.

16. Multi-stage blank feeding mechanism for compressing machines comprising means for feeding a blank to a predetermined position, means for holding the blank for a time at said position, and additional means for then feeding the blank further in an unbroken continuation of the same path.

17. In a machine of the class described, the combination of a blank magazine, means

- for operating upon a blank, rotating means for removing a blank from the magazine, and rectilinearly moving means for receiving the blank from the blank removing means, supporting and feeding it to the operating means. 40
18. In a compressing machine, the combination of a rotating mold carrier, a compressing mold upon the carrier, and mechanism for feeding blanks in their own planes to the mold in the direction of the axis of rotation of the carrier. 45
19. In a compressing machine, the combination of a rotating compressing mold, a blank magazine, and means for removing a blank from the magazine in the direction of rotation of the mold and feeding it in its own plane to the mold in the direction of the axis of rotation. 50
20. The combination, in a machine of the class described, of a magazine having a vertically movable side, a rotary picker for removing a blank from the bottom of the magazine and means for raising said movable side in timed relation to the action of the picker. 55
21. A bilaterally symmetrical lift magazine mounted for bodily adjustment longitudinally of the contained lifts and provided with means for adjusting the lateral halves of the magazine equally and oppositely toward or from each other. 60
22. A lift magazine comprising means for engaging the breast edges of contained lifts, a plurality of members for engaging the rear edges of the lifts, and means for adjusting the several rear edge engaging members independently toward or from the breast edge engaging means. 65
23. A compressing machine having a movable mold carrier, a compressing mold mounted upon the carrier, mold actuating mechanism mounted upon the carrier for applying pressure to the face of a blank in the mold, and mechanism upon the carrier for feeding blanks to the mold. 70
24. A compressing machine having a rotating mold carrier, a compressing mold mounted upon the carrier, mold actuating mechanism contained in the carrier, and reacting upon the carrier, for applying pressure to the face of a blank in the mold, and mechanism upon the carrier for feeding blanks to the mold. 75
25. A compressing machine having a movable mold carrier, a plurality of compressing molds mounted upon the carrier, mechanism upon the carrier for actuating all of the molds to apply pressure to blanks contained therein, and means upon the carrier for feeding blanks to all the molds. 80
26. A compressing machine having a rotating mold carrier, a plurality of compressing molds mounted upon the carrier, separate means for actuating each mold to apply pressure to a blank contained therein, and separate means for feeding blanks to the respective molds. 85
27. A compressing machine having a rotating mold carrier, a plurality of compressing molds mounted upon the carrier, and a toggle supported entirely upon the carrier for actuating each mold to compress a blank contained therein. 90

In testimony whereof we have signed our names to this specification. 75
